UNITED STATES PATENT OFFICE.

CHARLES WIRT, OF CHICAGO, ILLINOIS.

DESIGN FOR AN INSULATOR-BRACKET.

SPECIFICATION forming part of Design No. 21,377, dated March 8, 1892.

Application filed October 23, 1891. Serial No. 409,624. Term of patent 3½ years.

To all whom it may concern:

Be it known that I, CHARLES WIRT, a citizen of the United States, residing at Chicago, in the county of Cook and State of Illinois, 5 have invented and produced a new and original Design for Brackets for Electric Wires, of which the following is a specification.

My invention relates to improvements in designs for insulator-brackets for electric 10 wires. It is illustrated in the accompanying drawings, wherein—

Figure 1 is a side view of one of my brackets. Fig. 2 is a plan view thereof.

Like parts are indicated by the same letters 15 in both figures.

A is an insulator-support, which may be provided with the screw-threaded portion B.

C is the securing-plate.

D is a curved arm connecting the plate and

support, and E a flange or feather on the back 20 of such arm, also connecting the plate and support. The supporting-plate is in a plane substantially parallel to the axis of the insulator-support, while the straight portion of the plate D is parallel to such supporting-plate, 25 and the rib or feather E is at right angles thereto.

I claim—

The design for an insulator-bracket, herein shown and described, consisting of an insulator-support circular in cross-section, a flat supporting-plate, and a connecting-arm between the two, consisting of a curved connecting-plate and a flat rib on the back thereof. 30

CHARLES WIRT.

In presence of—

CELESTE P. CHAPMAN,
VIRGINIA WILLEY.
